[57] ABSTRACT

Apparatus is releasably connected to a packing assembly, the combination being lowered on a tubular running string until the packing assembly is disposed between a hanger body and a surrounding wellhead underlying a body of water. Rotation of the apparatus is transmitted through torque keys to the packing assembly to thread the latter along the hanger body and packoff the annular space between the hanger body and wellhead. The keys are retracted hydraulically from torque transmitting relation to the packing assembly, the apparatus being released from the packing assembly for retrieval to the drilling rig at the water surface.

APPARATUS FOR INSTALLING AND SETTING PACKING ASSEMBLIES IN WELLHEADS

The present invention relates to well apparatus, and more particularly to apparatus for effecting a seal of the region between a hanger body and a surrounding wellhead disposed at the upper end of the well bore.

In the drilling of oil and gas wells at an underwater location, a casing string is run into a well bore, the casing string being supported by a hanger body resting on a companion seat in a surrounding wellhead. The casing string is cemented in place and a suitable packing or seal assembly actuated to packoff the annular region between the hanger body and wellhead. Apparatus for performing the above method is illustrated in a number of United States patents, including applicant's U.S. Pat. Nos. 3,468,558, 3,468,559, 3,489,436 and 3,492,026.

In the present invention, the packing assembly is lowered from a drilling barge into position within the wellhead through use of a running string secured to a running and setting tool releasably connected to the packing assembly. Torque is transmitted from the setting tool to the packing assembly through one or a plurality of shiftable keys, or the like, which effect a threaded connection between the packing assembly and the casing hanger body, and then a packoff of the packing assembly between the casing hanger body and the surrounding wellhead. After the packoff has been effected, the one or more keys are retracted from torque transmitting relation to the packing assembly, which permits the running and setting tool to be released from the packing assembly and withdrawn to the drilling rig from which the apparatus is being operated. Prior to withdrawal of the keys from the packing assembly, the efficacy of the packoff can be tested. If found to leak, additional torque can be transmitted from the setting tool through the keys to the packing assembly to more firmly set the packing portion of the setting tool against the opposed sealing surfaces on the casing hanger body and the surrounding wellhead. If the leakage persists, the setting tool can be rotated in the opposite direction to unthread the packing assembly from the casing hanger body, permitting its withdrawal with the setting tool to the rig. If the pressure test is satisfactory, the keys are released from their torque transmitting relation to the packing assembly, the running tool then being released from the packing assembly to permit the running and setting tool to be withdrawn to the drilling rig.

In its more limited aspect, the torque transmitting keys of the setting tool are released from the packing assembly hydraulically in a facile and easy manner. The setting tool embodies a cylinder containing a suitable hydraulic fluid, pressure being imposed through the tubular running string secured to the running and setting tool on a piston to develop pressure in the fluid, this pressure then being imposed upon a piston which is operatively associated with the one or more keys to shift them from torque transmitting relation to the packing assembly.

A further objective of the invention is to provide a running and setting tool which can be lowered into a wellhead disposed at the floor of a body of water and readily placed in driving relation to a packing assembly located between a casing hanger body and the surrounding wellhead, for the purpose of either effecting further tightening of the packing assembly between the

casing hanger body and wellhead, or to release the packing assembly and effect its withdrawal to the rig at the surface of the water.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense.

Referring to the drawings:

FIG. 1 is a diagrammatic view of a subaqueous well bore drilled from a floating drilling vessel through associated equipment, including apparatus located at the floor of the body of water;

FIG. 2 is a quarter longitudinal section on an enlarged scale, with the setting tool in position to effect a packoff between a casing hanger body and a surrounding wellhead;

FIG. 3 is a vertical section on a smaller scale than FIG. 2, parts being shown in side elevation, of the invention in which the setting tool has been actuated to effect a packoff between a casing hanger body and a surrounding wellhead;

FIG. 4 is a view similar to FIG. 2, taken along the line 4—4 on FIG. 3, with the setting tool connected to the packing assembly;

FIG. 5 is a view similar to FIGS. 2 and 4 disclosing the torque transmitting keys of the setting tool released from the packing assembly;

FIG. 6 is a cross-section taken along the line 6—6 on FIG. 4;

FIG. 7 is a cross-section taken along the line 7—7 on FIG. 4;

FIG. 8 is an enlarged cross-section taken along the line 8—8 on FIG. 3;

FIG. 9 is a longitudinal section taken along the line 9—9 on FIG. 2; and

FIG. 10 is a longitudinal section taken along the line 10—10 on FIG. 9, but with the packing actuator sleeve shown threaded on the hanger body.

FIG. 1 is a diagrammatic illustration of a well bore A drilled below a body of water B from a drilling vessel C floating at the surface of the water, a marine riser pipe D extending from the drilling vessel downwardly to a suitable connector E attached to a blowout preventer stack F, which is connected through a suitable connector G to a wellhead housing H disposed within a base J mounted on the floor K of the body of water. The wellhead housing H has a string of casing L extending into the well bore. The upper end of the wellhead housing is secured to the connector member 10 by coupling dogs 11 received within circumferential recesses 12 in the wellhead housing. The coupling mechanism or connector is of any suitable type, such as the connector disclosed in U.S. Pat. No. 3,321,217. As shown in FIG. 3, a suitable seal or gasket ring 13 prevents leakage between the upper end of the wellhead housing H and the connector member 10 thereabove.

As illustrated in the drawings, a casing hanger body 14 has been lowered on a suitable running tool (not shown) into the wellhead housing H, this body having a landing ring 15 threadedly secured thereto which has a tapered surface 16 adapted to rest upon a companion seat 17 in the wellhead housing H, in order that the

hanger body can support a string of well casing M threadedly secured thereto and extending downwardly into the well bore. A split lock ring 18 is disposed in a peripheral groove 19 in the hanger body, resting upon the upper end of the landing ring 15. This lock ring is initially in a retracted position, but is adapted to be expanded outwardly into an opposed circumferential lock groove 20 in the wellhead housing H, to prevent upward movement of the casing string M and the hanger body 14 with respect to the wellhead housing.

Circumferentially spaced longitudinal flow passages or grooves 21 are provided in the lower portion of the hanger body 14 to permit circulating field and cement slurry to flow upwardly through the interior of the landing ring 15 and into the annulus 22 between the hanger body and wellhead housing H. The lower portion 22a of this annulus is defined between an external peripheral surface 23 on the hanger body above the flow passages and an opposed internal cylindrical sealing surface 24 in the wellhead housing. A suitable packing assembly 25 is shown in FIG. 3 as having been set in packed-off condition in the annular space 22a, sealing against the opposed external and internal surfaces 23, 24 and to also engage the lock ring 18 and expand it outwardly into the lock groove 20, as disclosed in FIGS. 3, 4 and 5. Actually, the circulating and cementing operations referred to above would have been performed after the hanger body 14 was lowered through the marine riser pipe D and into the wellhead H without the packing assembly 25 being present. After the ring 15 has landed on the wellhead shoulder, the split lock ring 18 would still have been disposed in retracted position within its peripheral groove 19.

It is to be noted that the casing hanger body 14 has an internal left-hand thread 26 and an internal groove 27, either of which can be operatively associated with a running tool (not shown) for lowering the hanger body and casing M in the well bore and wellhead housing. Moreover, a cylindrical internal sealing surface 28 is provided in the hanger body below its threads 26, for a purpose to be described hereinbelow. It should further be noted that the upper external portion of the hanger body is provided with an external right-hand thread 29, which coacts with the packing assembly 25 in effecting sealing of the latter against the opposed cylindrical surfaces 23, 24 on the hanger body 14 and wellhead H.

After the well casing M and hanger body 14 have been lowered into their appropriate position in the well bore and wellhead, and the circulating and cementing operations have been completed, the annular region 22a between the external and internal sealing surfaces on the casing hanger body and wellhead are to be engaged by the packing assembly, which is releasably connected to a running and actuating tool 30 that includes a body structure 31, the upper body member 32 of which is threadedly secured to the lower end of a tubular running string 33, by means of which the running and actuating tool and packing assembly combination are lowered toward the previously set hanger body 14 from the drilling vessel. The upper body member 32 has a reduced diameter portion 34 piloted within an outer, lower body member 35. An inner body member or cylinder 36 extends within the upper and lower body members, the upper end of the inner body member having a threaded connection 37 with the upper body member, its lower portion having a shoulder 38 bearing

against the lower end of the outer, lower body member 35 to hold the body members in appropriate assembled relation. Relative rotation between the upper body member 32 and the outer body member 35 is prevented by circumferentially spaced longitudinal shear pins 39 extending into opposed bores 39a in the upper body member and the upper end portion of the outer body member, these pins serving to transmit rotation and torque from the upper body member 32 to the outer body member 35.

The upper portion of the inner body member or cylinder 36 is spaced from an upper inner wall 40 of the outer body member 35 to provide an annular cylinder space 41 therebetween in which an annular hydraulic piston 42 can move longitudinally. This piston has an outwardly extending piston flange 43 movable with an annular cylinder space 44 of larger extent provided between the periphery 45 of the cylinder member 36 and an opposed inner wall 46 of the outer body member. The annular piston 42 is slidable along the periphery 45 of the cylinder and the inner wall 40 of the outer body member. Leakage of fluid between the cylinder 36 and the inner surface 47 of the piston is prevented by a seal ring 48 on the cylinder in slidable sealing relation to the inner surface of the piston, a seal ring 49 on the outer body member being in slidable sealing relation to the external surface 50 of the piston.

The cylinder has a central cylinder space 51 therein in which a central pump piston 52 is disposed, which is in slidable sealing relation to the inner wall of the cylinder, leakage of fluid being prevented between the central piston and cylinder wall by one or more seal rings 53 on the piston. The uppermost position of the central piston within the cylinder is limited by its engagement with a split expansible snap stop ring 54 held within a companion groove 55 in the cylinder and overlying the upper end of the piston. The piston is urged to its uppermost position by a helical compression spring 56 in the cylinder, the upper end of which bears against the piston and the lower end of which bears against a spring seat or shoulder 57 of the cylinder. The central cylinder space 51 communicates with the lower portion of the annular cylinder space 41 below the annular piston 42 through an orifice or port 58 extending from the lower portion of the central cylinder into the annular space. Leakage of fluid in a downward direction between the outer body member 35 and inner body member or cylinder 36 is prevented by a suitable seal ring 59 on the inner body member sealingly engaging against the inner wall of the outer body member below the port 58.

Hydraulic fluid fills the central cylinder space 51 with the central piston in its uppermost position, as well as the annular cylinder space 41 below the annular piston 42 when the latter is in its lowermost position within the annular cylinder, the flange 43 resting upon a shoulder 60 on the outer body member 35. This hydraulic fluid, such as a suitable oil, is introduced into the cylinder spaces 51, 41 through a central longitudinal passage 61 opening through the lower end of the inner body member 36 and communicating with the central cylinder space 51, this passage being closed by a threaded plug 62. Air and the like that might be present in the cylinder spaces can be dispelled through a longitudinal passage 63 extending from the annular cylinder space 41 to the lower end of the outer body member, which is also closed by a suitable threaded plug 64, after all of the spaces have been completely filled with

the hydraulic fluid, and with the annular piston 42 in its lowermost position, the central piston being disposed in its uppermost position against the stop ring 54. As described hereinbelow, the application of fluid pressure exerted through the running string 33 upon the central pump piston 52 will force the latter downwardly against the action of the return spring 56, the liquid passing through the orifice 58 and into the annular cylinder 41 for upward action on the annular fluid motor piston 42, shifting the latter upwardly within the annular cylinder. Relieving of the fluid pressure acting downwardly on the central piston 52 allows the return spring 56 to shift the central piston back to its uppermost position, creating a suction force that will pull the annular piston 42 back downwardly to its initial position.

The body structure 31 is releasably secured to the annular packing assembly that, as noted above, is to seal the space 22a between the hanger body and wellhead, the releasable connection being made through the intervention of an actuating sleeve 65 which has an internal right-hand thread 29a adapted to mesh with the internal thread 29 on the hanger body 14. As illustrated, the packing assembly 25 includes an upper supporting ring 66, the upper portion of which encompasses a reduced diameter lower portion 65a of the actuating sleeve. A swivel connection is provided between the upper support ring and actuating sleeve. As disclosed, such swivel connection includes a swivel ring 67 mounted in an external groove 68 in the lower portion of the actuating sleeve, this ring also being received within an opposed internal groove 69 in the upper support ring. With the actuating sleeve 65 and upper ring 66 swivelly connected together, the upper end of the support ring engages a thrust bearing ring 70, which, in turn, bears against a downwardly facing shoulder 71 of the actuating sleeve. A similar thrust bearing ring 72 engages the lower end of the actuating sleeve and an opposed upwardly extending shoulder 73 on the upper support ring 66. As described hereinbelow, the actuating sleeve 65 can rotate without its rotation being transmitted to the upper supporting ring 66. The latter, however, cannot move longitudinally with respect to the actuating sleeve 65.

The packing assembly further includes an elastomer packing sleeve 74, the upper end of which is connected to the lower portion of the upper supporting ring 66 and the lower end of which is connected to a lower abutment ring 75. The specific construction of the packing assembly per se forms no part of the present invention. However, as specifically illustrated, the connections are provided by dovetails 76 on the upper and lower ends of the packing sleeve received within companion dovetail grooves 77 in the upper supporting ring and lower abutment ring. These rings also have metallic lip seals 78 facing each other and encompassing the upper and lower portions of the elastomer packing sleeve 74.

At the drilling rig R mounted on the drilling vessel C, the packing assembly 25 and actuating sleeve 65 are releasably secured to the body structure 31 by a plurality of lock pins 79 extending laterally from a reduced diameter portion 80 of the outer body member piloted within the upper portion of the actuating sleeve 65, these pins being movable within J-slots 81 in the actuating sleeve. Each slot includes a horizontal portion 82 opening at one end into a vertical portion 83 that opens upwardly through the upper end of the actuating sleeve

65. In mounting the actuating sleeve and packing assembly on the body structure 31, the actuating sleeve 65 is moved upwardly along the lower body member 35 in order that its lock pins 79 can enter the vertical entry portions 83 of the associated J-slots, after which the actuating sleeve is rotated to relatively shift the lock pins within the horizontal portions 82 and toward the closed ends of the horizontal slot portions, thereby securing the actuating sleeve and body structure for longitudinal movement together. When the lock pins are at the innermost portion of the J-slots, a plurality of circumferentially spaced, longitudinally extending torque keys 84 will shift downwardly within the vertical portions 83 of the J-slots, providing a rotatable driving connection 15 between the keys and the actuating sleeve 65. These keys move longitudinally within vertical guide grooves 85 in the outer body member. When positioned within the J-slots 81 in the actuating sleeve, they prevent relative rotation between the body structure 31 and the actuating sleeve 65 and packing assembly 25, the J-pins then supporting the latter for longitudinal movement with the body structure.

The upper portions of the torque keys 84 are threadedly secured to longitudinally extending tension screws 25 86 passing through vertical counterbores 87 in the upper body member 32, the screw shanks extending through longitudinal bores 88 in the upper body member of slightly greater diameter than the shank diameter, with the screws terminating in upper heads movable in upper counterbores 90 in the upper body member opening through its upper end. Each screw head engages the base of its upper counterbore 90 to limit the extent of downward movement of the keys within their companion vertical guide grooves 85, such downward movement being effected by a helical compression spring 91 in the counterbore 87 surrounding each screw, with its lower end engaging the upper end of the key and its upper end engaging the upper end of the lower counterbore. Each key 84 is confined for longitudinal movement in its companion groove 85 by the tension screw 86, and also by a cap screw 92 suitably mounted and secured in the outer body member 35 and extending through a longitudinal slot 93 in the lower portion of each key. The key 84 is movable upwardly within its companion groove 85 to an appropriate extent in which the key is shiftable completely out of the vertical run 83 of the J-slot, when each J-pin 79 is located within the horizontal run 82 of its J-slot.

The keys are shiftable upwardly out of the vertical runs 83 of the J-slots upon upward movement of the annular piston 42 within the annular cylinder 41. Such upward movement of the annular piston is transmitted through radial key retracting pins or screws 94 threadedly secured to the piston flange 43 and extending through vertical slots 95 in the outer body member 35 into elongate inner recesses 96 in the keys. Upward movement of the piston 42 will cause the screws 94 to engage the upper side 97 of the recesses and shift the keys 84 upwardly in their grooves 85 and out of the vertical runs 83 of the J-slots against the force of the compressed holding springs 91. When the annular piston 42 is not subject to the hydraulic pressure generated by downward shifting of the central piston 52, the holding springs 91 will shift the keys 84 downwardly to the positions illustrated in FIGS. 2, 3 and 4. The position and actuation of the annular pistons 42, 43 can be viewed through one or more radial viewing windows 98 ex-

tending through the outer body member 35 to one side of the key grooves 85.

In the use of the apparatus, after the hanger body 14 has been landed in the wellhead housing H and the casting M cemented in place, the running and actuating tool 30 should preferably be pressure tested to verify the absence of leakage, pressure being applied to the central piston intermittently to cause the annular piston 42, 43 of the fluid motor to move upwardly and downwardly in its annular cylinder 41, 44, the movement of the annular piston being viewed through the inspection windows 98. If foreign substances are restricting movement of the annular piston, appropriate flushing action can be provided by a flushing liquid flowing through the inspection windows.

After the tool has been checked to verify its proper operation, and while maintaining pressure in the tool, the actuating sleeve 65, with the packing assembly 25 supported thereby, is shifted along the lower body member 35 until the vertical runs 83 of the J-slots receive the J-pins 79, the actuating sleeve then being turned to move the J-pins relatively toward the far ends of the horizontal J-portions 82 of the slots. The vertical portions 83 of the J-slots are then in alignment with the keys 84. The pressure is then relieved, which permits the springs 91 to shift the keys downwardly through the vertical portions 83 of the J-slots and across the horizontal portions, which also precludes relative turning between the actuating sleeve 65 and the running tool 30.

The tubular running string 33 is then secured to the upper end of the upper body member 32, and the assembly is lowered on the running string through the marine riser D to the hanger body 14. The lower body member 36 will enter the hanger body, and the lower thread turn 29a on the actuating sleeve will engage the upper thread turn 29 on the hanger body (FIG. 2). The running string 33 and body structure 31 are then rotated, such rotation being transmitted through the torque keys 84 to the actuating sleeve 65, the latter threading downwardly along the hanger body 14 and moving the packing assembly 25 into the seal space 22a between the hanger body and wellhead housing. Sufficient rotation of the actuating sleeve 65 is required to cause the abutment ring 75 to engage the lock ring 18 and shift it outwardly into the lock groove 20 in the wellhead H, the abutment ring coming to rest upon the hanger body shoulder 100. Continued turning of the actuating sleeve then shifts the upper support ring 66 toward the abutment ring 75 to shorten and compress the packing sleeve against the external and internal surfaces 23, 24 on the hanger body 14 and wellhead H, further compression of the elastomer packing sleeve expanding the lip seals 78 against such surfaces to provide metallic seals thereagainst, supplementing the elastomer sealing action of the packing sleeve 74. At this time, the lower body member 35 will have moved downwardly within the hanger body 14 to place seal rings 101 on the body member in sealing engagement with the internal cylindrical seat 28 on the hanger body.

A blowout preventer F can then be closed on the running string 33 and pressure applied to the fluid in the annulus around the running string to test the energized torque-set seal. If the pressure test is satisfactory, pressure is imposed on the fluid in the running string 33, which will shift the central pump piston 52 downwardly

in its cylinder 51 to apply pressure to the hydraulic fluid therein and effect elevation of the annular piston 42, 43 within the annular cylinder 41, 44. Such upward movement causes the retracting screws 94 to engage the upper ends 97 defining the key recesses 96 to lift the keys 84 out of the horizontal and vertical runs of the J-slots 81. Left-hand rotation of the running string 33 and tool 30 then shifts the J-pins 79 of the running tool along the horizontal slots to the vertical slots 83, permitting the running tool to be elevated, its J-pins moving completely out of the J-slots and fully releasing the running tool 30 from the actuating sleeve 65. The actuating sleeve remains threaded to the hanger body 14 to retain the packing assembly 25 in its packed-off condition between the hanger body 14 and wellhead H. The running tool 30 can then be withdrawn through the marine riser D to the drilling vessel C and rig R.

Assuming that the test indicates the packing assembly does not hold the desired pressure, additional torque can be applied to the running string 33 to further tighten the actuating sleeve 65 in a downward direction prior to withdrawal of the torque keys 84 from the J-slots. In the event that the packing assembly still does not hold pressure, the running tool can be used to recover the actuating sleeve 65 and packing assembly 25 carried thereby by rotating the running string 33 and tool 30 to the left, which will unthread the actuating sleeve 65 from the hanger body 14, permitting the entire assembly to be elevated by the running string 33 through the marine riser to the rig floor.

I claim:

1. Apparatus for effecting a seal between a wellhead and a hanger disposed therein for supporting a tubular string extending into a well bore: comprising a running tool having a body structure and connectible to a running string; packing means; means releasably connecting said packing means to said body structure to enable said packing means to be placed in sealing relation to the hanger; actuatable means movable on said body structure for preventing release of said connecting means; and shifting means for moving said actuatable means on said body structure to a position permitting release of said connecting means.

2. Apparatus as defined in claim 1; said actuatable means engaging said packing means and being responsive to movement of said body structure to move said packing means into sealing relation to the hanger.

3. Apparatus as defined in claim 1; said packing means being adapted to seal the annular space between the wellhead and hanger; said actuatable means engaging said packing means and being responsive to movement of said body structure to move said packing means into sealing relation to the hanger and wellhead to seal the annular space therebetween.

4. Apparatus as defined in claim 1; said packing means having a first thread companion to a second thread on the hanger; said actuatable means engaging said packing means and being responsive to rotation of said body structure to feed said first thread along the second thread and move said packing means into sealing relation to the hanger.

5. Apparatus as defined in claim 1; said packing means being adapted to seal the annular space between the wellhead and hanger; said packing means having a first thread companion to a second thread on the hanger; said actuatable means engaging said packing means and being responsive to rotation of said body

structure to feed said first thread along the second thread and move said packing means into sealing relation to the hanger and wellhead to seal the annular space therebetween.

6. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening.

7. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said actuatable means engaging said packing means and being responsive to movement of said body structure to move said packing means into sealing relation to the hanger.

8. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said packing means being adapted to seal the annular space between the wellhead and hanger; said actuatable means engaging said packing means and being responsive to movement of said body structure to move said packing means into sealing relation to the hanger and wellhead to seal the annular space therebetween.

9. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said packing means having a first thread companion to a second thread on the hanger; said actuatable means engaging said packing means and being responsive to rotation of said body structure to feed said first thread along the second thread and move said packing means into sealing relation to the hanger.

10. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said packing means being adapted to seal the annular space between the wellhead and hanger; said packing means having a first thread companion to a second thread on the hanger; said actu-

atable means engaging said packing means and being responsive to rotation of said body structure to feed said first thread along the second thread and move said packing means into sealing relation to the hanger and wellhead to seal the annular space therebetween.

11. Apparatus as defined in claim 1; said shifting means being responsive to fluid pressure for moving said actuatable means to said position permitting release of said connecting means.

10 12. Apparatus as defined in claim 1; said shifting means being responsive to fluid pressure in the running string for moving said actuatable means to said position permitting release of said connecting means.

15 13. Apparatus as defined in claim 1; said shifting means being responsive to fluid pressure for moving said actuatable means to said position permitting release of said connecting means; and spring means on said body structure engaging said actuatable means to yieldably resist movement of said actuatable means to said position permitting release of said connecting means.

20 14. Apparatus as defined in claim 1; said shifting means being responsive to fluid pressure in the running string for moving said actuatable means to said position permitting release of said connecting means; and spring means on said body structure engaging said actuatable means to yieldably resist movement of said actuatable means to said position permitting release of said connecting means.

25 15. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means being responsive to fluid pressure in the running string for moving said actuatable means from said opening to enable said pin to move through said opening.

30 16. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means being responsive to fluid pressure in the running string for moving said actuatable means from said opening to enable said pin to move through said opening; and spring means on said body structure engaging said actuatable means to yieldably resist movement of said actuatable means from said opening.

35 17. Apparatus as defined in claim 1; said shifting means including a fluid motor in said body structure for moving said actuatable means, and a fluid pump in said body structure responsive to fluid pressure in the running string for pressuring fluid between said pump and motor to effect operation of said motor.

40 18. Apparatus as defined in claim 5; said shifting means including a fluid motor in said body structure for moving said actuatable means, and a fluid pump in said body structure responsive to fluid pressure in the running string for pressuring fluid between said pump and motor to effect operation of said motor.

45 19. Apparatus as defined in claim 10; said shifting means including a fluid motor in said body structure for moving said actuatable means, and a fluid pump in said

body structure responsive to fluid pressure in the running string for pressuring fluid between said pump and motor to effect operation of said motor.

20. Apparatus as defined in claim 10; said shifting means including a fluid motor in said body structure for moving said actuatable means, and a fluid pump in said body structure responsive to fluid pressure in the running string for pressuring fluid between said pump and motor to effect operation of said motor; and spring means on said body structure engaging said actuatable means to yieldably resist movement of said actuatable means from said opening.

21. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said actuatable means including one or more keys slidable vertically on said body structure and disposed in said one or more openings.

22. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said actuatable means including one or more keys slidable vertically on said body structure and disposed in said one or more openings; and spring means engaging said one or more keys to yieldably retain said one or more keys in said one or more openings.

23. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said packing means being adapted to seal the annular space between the wellhead and hanger; said packing means having a first thread companion to a second thread on the hanger; said actuatable means engaging said packing means and being responsive to rotation of said body structure to feed said first thread along the second thread and move said packing means into sealing relation to the hanger and wellhead to seal the annular space therebetween; said actuatable means including one or more keys slidable vertically on said body structure and disposed in said one or more openings.

24. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said packing means being adapted to seal the annular space between the wellhead

and hanger; said packing means having a first thread companion to a second thread on the hanger; said actuatable means engaging said packing means and being responsive to rotation of said body structure to feed said first thread along the second thread and move said packing means into sealing relation to the hanger and wellhead to seal the annular space therebetween; said actuatable means including one or more keys slidable vertically on said body structure and disposed in said one or more openings; and spring means engaging said one or more keys to yieldably retain said one or more keys in said one or more openings.

25. Apparatus as defined in claim 1; said releasable connecting means including a pin on said body structure movable relatively along a slot in said packing means, said slot including an opening through the upper end of said packing means; said actuatable means being disposed in said opening to retain said pin in said slot; said shifting means moving said actuatable means from said opening to enable said pin to move through said opening; said packing means being adapted to seal the annular space between the wellhead and hanger; said packing means having a first thread companion to a second thread on the hanger; said actuatable means engaging said packing means and being responsive to rotation of said body structure to feed said first thread along the second thread and move said packing means into sealing relation to the hanger and wellhead to seal the annular space therebetween; said actuatable means including one or more keys slidable vertically on said body structure and disposed in said one or more openings; and spring means engaging said one or more keys to yieldably retain said one or more keys in said one or more openings; said shifting means including a fluid motor in said body structure for moving said actuatable means, and a fluid pump in said body structure responsive to fluid pressure in the running string for pressuring fluid between said pump and motor to effect operation of said motor.

26. A running and setting tool for operating apparatus operatively associated with a well bore: comprising a body structure having means for connection to a running string; connecting means on said body structure adapted to be releasably connected to the apparatus; actuatable means movable on said body structure and adapted to engage the apparatus to prevent release of said connecting means from the apparatus; and shifting means for moving said actuatable means on said body structure to a position disengaged from the apparatus to permit release of said connecting means from the apparatus.

27. A running and setting tool as defined in claim 26; said actuatable means being engageable with the apparatus to transmit torque from the running string and body structure to the apparatus.

28. A running and setting tool as defined in claim 26; said shifting means being responsive to fluid pressure for moving said actuatable means to said position permitting release of said connecting means.

29. A running and setting tool as defined in claim 26; said shifting means being responsive to fluid pressure in the running string for moving said actuatable means to said position permitting release of said connecting means.

30. A running and setting tool as defined in claim 26; said shifting means including a fluid motor in said body structure for moving said actuatable means, and a fluid

pump in said body structure responsive to fluid pressure in the running string for pressuring fluid between said pump and motor to effect operation of said motor.

31. A running and setting tool as defined in claim 26; said actuatable means including one or more keys slideable vertically on said body structure.

32. A running and setting tool as defined in claim 26; said actuatable means including one or more keys slideable vertically on said body structure; and spring means engaging said one or more keys to urge said one or more keys downwardly along said body structure.

33. A running and setting tool as defined in claim 26; said actuatable means including one or more keys slideable vertically on said body structure; said shifting means including a fluid motor in said body structure for

moving said actuatable means, and a fluid pump in said body structure responsive to fluid pressure in the running string for pressuring fluid between said pump and motor to effect operation of said motor.

34. A running and setting tool as defined in claim 26; said actuatable means including one or more keys slideable vertically on said body structure; and spring means engaging said one or more keys to urge said one or more keys downwardly along said body structure; said shifting means including a fluid motor in said body structure for moving said actuatable means, and a fluid pump in said body structure responsive to fluid pressure in the running string for pressuring fluid between said pump and motor to effect operation of said motor.

UNITED STATES PATENT OFFICE
CERTIFICATE OF CORRECTION

PATENT NO. : 3,903,965
DATED : September 9, 1975
INVENTOR(S) : ARTHUR G. AHLSTONE

It is certified that error appears in the above-identified patent and that said Letters Patent are hereby corrected as shown below:

Column 3, line 13: change "field" to --fluid--.

Column 6, line 29: after "heads" insert --89--.

Signed and Sealed this
tenth Day of February 1976

[SEAL]
